UNITED STATES PATENT OFFICE

152,008

DESIGN FOR A UTILITY CREEPER WITH ILLUMINATOR OR THE LIKE

Stephen J. Lucas, Chicago, Ill.

Application June 25, 1947, Serial No. 139,906

Term of patent 14 years

(Cl. D14—3)

To all whom it may concern:

Be it known that I, Stephen J. Lucas, a citizen of the United States, residing at Chicago, in the county of Cook and State of Illinois, have invented a new, original, and ornamental Design for a Utility Creeper With Illuminator or the like, of which the following is a specification, reference being had to the accompanying drawing, forming part thereof.

In the drawing:

Figure 1 is a perspective view of a utility creeper with illuminator showing my new design;

Figure 2 is a side elevational view of the same; and

Figure 3 is a rear elevational view of the same.

The characteristic features of my design reside in the portions shown by means of full lines in the drawing.

I claim:

The ornamental design for a utility creeper with illuminator or the like, as shown and described.

STEPHEN J. LUCAS.
